UNITED STATES PATENT OFFICE.

HERMON H. KINSMAN AND WILLIAM M. GAYLOR, OF NEW YORK, N. Y.

GAME.

1,381,472.

Specification of Letters Patent. Patented June 14, 1921.

Application filed October 9, 1919, Serial No. 329,483. Renewed August 20, 1920. Serial No. 404,958.

To all whom it may concern:

Be it known that we, HERMON H. KINSMAN and WILLIAM M. GAYLOR, citizens of the United States, residing at New York, in 5 the county of New York and State of New York, have invented certain new and useful Improvements in Games, of which the following is a specification.

The present invention relates to an indoor 10 or parlor game which is designated "African golf," since it presents all the features of the outdoor sport.

The game contains a playing field or fairway, a driving tee, a playing table, a putting green and a course indicator.

The drawings illustrate a preferred embodiment of the invention. However, it is to be understood that in adapting the same to meet different conditions, various changes in 20 the form, proportion, and minor details of construction may be resorted to without departing from the nature of the invention as claimed hereinafter.

Referring to the drawings hereto attached; 25 Figure 1 is a diagrammatic view of a game embodying the invention;

Fig. 2 is a detail view of a portion of the playing field on a larger scale;

Fig. 3 is a detail view of the playing table, 30 the same being illustrated on a larger scale;

Fig. 4 is an enlarged detail view of a portion of the indicator of the golf course; and

Fig. 5 is a fragmentary view of a portion 35 of the putting green on a larger scale.

Corresponding and like parts are referred to in the following description and indicated in the several views of the drawings by like reference characters.

While it is preferred to have all the parts 40 appear on the surface of a table or board, nevertheless they may be separate. However, there is a coöperation between the several parts as will appear more fully herein-after. The playing field or fairway is designated by the reference letter A and 45 comprises a plurality of parallel strips which are subdivided by transverse lines to form squares or spaces which are adapted to receive the markers or game pieces. The 50 parallel strips are preferably of contrasting color to admit of the path or course of each player being readily determined and thereby avoid confusion and mistake. These parallel strips of contrasting color are separated 55 by intermediate strips of uniform color,

thereby making the playing courses more pronounced and reducing the chances for mistake in the position and advancing of the markers or game pieces. The transverse spaces are designated by numbers in multiples of ten for convenience of reckoning. The transverse lines are extended beyond the sides of the playing field and the numbers on the projecting ends and at opposite sides of the playing field extend in reverse directions for convenience of reading from either end of the field. The shape of the playing field is immaterial but it is preferred to have the same curved in its length and approximately of U form, one leg or side being 60 shorter than the other leg or side so as to make provision for the putting green and course indicator. The space comprised between the legs is utilized for receiving the playing table. At one end of the playing 65 field or fairway A is located the driving tee B which designates the starting point from which each marker or game piece begins its travel toward the holes in the playing of the game. For convenience, the driving tee is 70 likewise of contrasting color, the spaces and coloring agreeing with the strips and coloring of the playing field. At intervals in the length of the playing field, descriptive matter appears which has a controlling influence 75 on the playing of the game and usually is of a nature to penalize the player so as to increase the number of plays or strokes necessary to hole out.

The rectangular-shaped figure designated 90 by the letter C is subdivided into squares by intersecting lines, there being ten squares above and ten squares below a heavy medial line. The squares above the horizontal line are numbered from 1 to 10 and are designated by the plus character. The squares below the medial horizontal line are likewise numbered from 1 to 10 and are designated by the minus character. These squares are of contrasting color to admit of 95 their being readily distinguished one from the other. Each of the squares bears certain numbers which determine the distance of movement of the markers or game pieces on the playing field. The putting green C 100 is had recourse to by a player when within a short distance of the hole at approximately 20 yards. The plus squares designate yards to be added, whereas the minus squares 105 designate yards to be subtracted. The dif- 110

ference between selected numbers of plus and minus squares determines the distance to be registered on the playing field so as to hole out.

5 The playing table D is of circular form and is subdivided by concentric circles and radial lines into sector and arcuate-shaped spaces. There are ten sector-shaped spaces which correspond with the ten plus squares 10 and the ten minus squares of the putting green. The sector-shaped spaces are designated at their inner or smaller ends by numerals which are in consecutive order, from 1 to 10 inclusive. The sector-shaped spaces are 15 of contrasting color to facilitate distinction. The arcuate spaces of each sector-shaped space bear club names and numbers, the latter designating the yards to be registered on the playing field by each player as he 20 makes a play. The club names in each sector-shaped space correspond in the same circular space. The numbers opposite each club name indicate the yardage to be recorded on the playing field. It is observed 25 that the outermost circular space of the playing table is designated by the term "Putt" and the same may be plus or minus. The numbers appearing in each outer arcuate space agree with the numbers on the 30 squares of the putting field corresponding with like designating numerals. The plus and minus squares of the putting green designated by the numerals 1 bear the indicating numbers 1, 2, 3 and 15. The outermost arcuate space of the sector-shaped division 1 of the playing table bears corresponding numbers 1, 2, 3 and 15. By comparison it will be observed that corresponding squares of the putting green bear 35 numbers agreeing with the outermost sector-shaped putting spaces of like designated sector-shaped divisions of the playing table.

The letter E designates the course indicator, one-half being provided with numbers 40 corresponding to the yards for each of the holes in order and the other half bearing spaces upon which numbers may be written agreeing with the yards for each hole of any selected golf course. Thus a player may 45 adapt the game to his own or any particular course and thereby become perfectly familiar with the various distances and other points.

The markers or game pieces are not shown 50 and may be of any nature, such as the men or pieces used in playing checkers, chess or similar games requiring movable pieces. In order that the method of playing the game may be understood, the following is submitted, it being understood that there may 55 be as many players as there are designated strips in the playing field. The players may take turn and each selects a marker or game piece and a path or strip on the playing field. The clubs designated in the arcuate 60 spaces of the sector-shaped divisions of the playing table determine the yardage or distance to be recorded on the playing field. It is observed that the club, "Driver" designates the highest yardage 65 or distance and this club is naturally selected by the player. The position of the club is determined by chance, either by throwing dice or spinning a pointer or in other determinate way. The player having 70 selected the club, "Driver" determines the relative position of the same by chance in the manner stated. Suppose, for instance, that the number determined is 5. By referring to the playing table, the distance indicated is 220 yards. It is assumed that the indicated golf course is that appearing on the left hand portion of the golf course indicator. On reference thereto, it will be seen that the first hole is 325 yards. The play 75 made entitles the player to record 220 yards on the playing field, hence the marker or game piece is moved from the "Driving tee B" to a position designated by 220 on the playing field. The player must now make 80 105 yards in order to reach the first hole. He selects as his next club "Mashie." The relative position of the club is determined by chance in the manner stated and 7 is the designated number. By referring to the 85 playing table and to the club "Mashie" in the divisional sector-shaped space 7, 100 yards is the number to be registered which added to the 220 yards previously recorded 90 entitles the player to move his marker or game piece to the 320 yardage on the playing field. As the first hole is 325 yards, the player must still make 5 yards to hole out. He now elects to "putt" and determines the 95 square on the putting field by chance and the square designated by the play is 6. The player now places a marker or game piece on the plus square 6 of the putting green and this square bears the numbers 1, 8 and 100 16. It will be observed however, that neither 110 one of these numbers entitles the player to move the exact distance on the playing field in order to hole out. The player therefore elects a "minus putt" and determines the 115 square by chance either by throwing dice or fitting a pointer, as herein stated. The square designated is 8 which is covered by a marker or game piece. This square bears the numbers 1, 2, 3 and 19. The number 8 appearing on the plus square 6 and the number 3 appearing on the minus square 8 results in the number 5 by subtracting the number 3 from the number 8, which is 5, the number required to hole out by adding to the 320 previously registered on the playing field. It will thus be understood that the player has taken four plays or strokes to 120 make the first hole and this is designated 125

par-golf, as indicated on the golf course E. The next hole is played in the same manner starting with the board clear of markers. Golf clubs are selected by the player according to the distance to be played and the distances are so laid out that the same club will be played in the game which would be used in the out-door sport, which results in familiarizing one with the game. The 10 player winning the most holes or making the round in the least number of strokes wins the match. It will be observed that the game will enable one to play any game that may be played on a golf course or links.

15 Having thus fully described our invention, what we claim as new and desire to secure by Letters Patent is:—

1. In a game of the character set forth, a playing field subdivided into spaces which 20 are consecutively numbered, a putting green consisting of a rectangular field subdivided into spaces which are separated by a divisional line, the spaces upon opposite sides of the divisional line being correspondingly 25 designated and bearing corresponding indicating matter and numbers, one set of spaces being further designated by the plus sign

and the other set of spaces being designated by the minus sign.

2. A game of the character specified, comprising a playing field including parallel strips which are subdivided into spaces which are consecutively numbered, a starting point at one end of the playing field, a playing table subdivided by concentric circles and radial lines into sector-shaped divisions and arcuate-shaped spaces, the divisional spaces bearing designating matter and the arc-shaped spaces bearing names and numbers, a putting green subdivided into a 30 like number of plus and minus squares which bear corresponding indicating characters and numbers and a golf course for indicating the various distances on the playing field determining the objective points of 35 play.

In testimony whereof we affix our signatures in presence of two witnesses.
